UNITED STATES PATENT OFFICE.

JOHN MULLER, OF FLUSHING, NEW YORK, ASSIGNOR TO DECORATIVE ARTS LEAGUE,
OF JERSEY CITY, NEW JERSEY, A CORPORATION OF NEW JERSEY.

DESIGN FOR A GRATE.

Application filed November 18, 1922. Serial No. 4,331. Term of patent 14 years.

To all whom it may concern:

Be it known that I, JOHN MULLER, a citizen of the United States, residing at Flushing, in the county of Queens and State of New York, have invented a new, original, and ornamental Design for a Grate, of which the following is a specification, reference being had to the accompanying drawing, forming part thereof.

The figure is a perspective view of the grate showing my new design.

I claim:

The ornamental design for a grate, as shown.

In testimony whereof, I have hereunto signed my name.

JOHN MULLER.
